ELECTROMAGNETIC RELAY

Gunnar Börge Knös, Eindhoven, Netherlands, assignor to N. V. Philips' Gloeilampenfabrieken, Eindhoven, Netherlands

Application August 7, 1937, Serial No. 157,996
In Germany September 11, 1936

2 Claims. (Cl. 200—1)

My invention relates to electromagnetic relays of the type in which spring contact members are insulatingly arranged in a stack, and are moved from their position of rest upon response of the relay.

In such relays considerable difficulty arises in transmitting motion to these members, particularly when a large number of contact members are to be operated by a single armature. In present constructions only one contact member is directly operated by the armature, and intermediate members are provided to transmit the movement from the first contact member to the second, etc. Such constructions however, are rather complicated, difficult to assemble, and frequently unreliable in operation because of the forces introduced by the shifting of the intermediate members.

The object of my invention is to eliminate the above difficulties, and to produce a simple, cheap and reliable relay.

According to the invention, I transmit the movement of the armature directly to each contact member. More particularly I provide between the contact members and armature, a connecting member having cross arms extending between the contact members to move the same from their position of rest upon actuation of the armature.

In order that the invention may be clearly understood and readily carried into effect I shall describe the same in more detail with reference to the accompanying drawing in which:

Figure 1 is a side view of a relay embodying the invention.

Fig. 2 is a sectional view along line 2—2 of Fig. 1 with certain parts omitted:

Fig. 3 is a sectional view along line 3—3 of Fig. 2;

The relay illustrated in Fig. 1 comprises a magnetic core having a strip-shaped portion 20, a coil 1, and an armature 2 pivoted on the end of portion 20 and held in its open position by a leaf spring 15. Secured to portion 20 is a support 4 carrying a stack of contact members, and insulating members 8. The contact members comprise three armature springs 6, a stationary make strip 1, and two break springs 21. Springs 21 and the two lower armatures 6 are supported in their position of rest by stationary strips 22. The members 6, 1, 21 and 22, and insulating members 8 are held together in the stack by a clip 9 secured to support 10, in the manner described in my co-pending U. S. Patent application Ser. No. 157,996, filed August 7, 1937.

In accordance with the invention, each armature spring 6 is directly connected to armature 2 and is moved from its rest position upon energization of coil 1. For this purpose a member 3 extends on the outside of the stack and is provided with cross-members 11, 12 and 13 engaging the lower surface of springs 6.

As shown more clearly in Fig. 2, member 3 is formed of a single piece of metal or insulating material and has a bottom portion 23 loosely fitting into a slot in armature 2, and two arm portions 24 extending substantially perpendicular to the longitudinal axis of spring 6. The cross arms 11, 12 and 13, which are of insulating material, are removably fitted between arms 24—24 and 15 are provided with notches 25 which cooperate with the arms 24 as shown in Fig. 3.

As shown in Fig. 2, cross arm 11 is inserted from the top and rests upon protuberances 15 of arms 24. To allow insertion of members 12 and 13, the arms 24 are provided with notches 14 at a point above the corresponding protuberances 15. It will be noted that member 3 can be used with less than three armatures in which case some of the cross members are not used.

While I have described my invention in connection with specific examples, I do not wish to be limited thereto but desire the appended claims to be construed as broadly as permissible in view of the prior art.

What I claim is:

1. In a relay, an armature, a plurality of flexible elongated flat contact springs arranged in a stack, a member actuated by said armature and extending on both sides and substantially perpendicularly to the longitudinal axis of said springs, and flat cross arms connected to said member and serving to move said springs from their position of rest, said cross arms extending between said springs with their active surfaces lying in planes parallel to the plane of the springs.

2. In a relay, an armature, a plurality of flexible contact springs arranged in a stack, a strip-shaped member actuated by said armature and having portions extending substantially perpendicularly to said springs and outside the stack, the edges of said portions facing the stack being provided with notches and protuberances, and cross-arm members supported by said protuberances and cooperating with said springs, the ends of said cross-arm members being provided with slots embracing said extending portions.

GUNNAR BÖRGE KNÖS.
